(57) **ABSTRACT**

Compensation circuits, compensated voltage regulators, and methods are provided for stabilizing voltage regulators, or other circuits that use operational amplifiers, over a wide range of output current. The described techniques provide a zero whose frequency varies linearly with an output current, and which can be used to track and compensate for a pole whose frequency similarly varies with the output current. The variable-frequency zero is created using a compensation capacitor placed in series with a variable resistance, wherein the resistance is configured to vary linearly with the output current. A pole-tracking zero generated in this way may be used to overcome difficulties encountered when the gain of a system includes a pole whose frequency varies with output current, and serves to improve the phase margin of amplifier circuitry, including that used within voltage regulators, and/or serves to ensure stability over a wide range of output current.

POLE-ZERO TRACKING COMPENSATION NETWORK FOR VOLTAGE REGULATORS

TECHNICAL FIELD

The present application relates to a compensation network for a voltage regulator, wherein the compensation network provides a zero whose frequency follows an output current of the voltage regulator so as to compensate for a variable pole of the voltage regulator.

BACKGROUND

Linear voltage regulators, including low dropout (LDO) regulators, use a pass device to provide a relatively constant voltage level to an output load. A control signal provided to a control terminal of the pass device determines the amount of current flowing through the pass device, so as to maintain the relatively constant voltage level. In a common implementation of an LDO regulator, the pass device is a p-channel metal-oxide semiconductor field-effect transistor (pMOSFET) and the control terminal is a gate of the pMOSFET. A typical linear voltage regulator also includes an error amplifier that generates the control signal based upon the difference between a reference voltage and a portion of the output voltage. As the output voltage decreases below a desired output voltage, the error amplifier and the pass device increase the amount of current flowing to the output load. As the output voltage increases above the desired output voltage, the current flow to the output load is decreased. In this way, a linear regulator uses a negative feedback loop to maintain the relatively constant voltage level provided to the output load.

The loop gain of a linear regulator as described above is frequency-dependent, and the linear regulator must be designed to ensure stability. The loop gain, and associated frequency and phase responses, of the linear regulator may be characterized using poles and zeros. The poles and zeros are determined from impedances within the linear regulator and associated circuitry, e.g., the output load and capacitor. In an ideal negative feedback system, the overall phase response is 180°, so that the feedback perfectly cancels the error at the output, e.g., the output voltage of a linear regulator. If the overall phase response approaches 0°, 360°, or a multiple thereof, the feedback becomes additive to the error, and the loop becomes unstable for gains greater than 0 dB. The loop stability is characterized using phase margin ϕ_M , which is the difference between 180° and the modulus of the critical phase ϕ_C , where the critical phase ϕ_C is the phase response at the frequency where the magnitude response is 0 dB, i.e., $\phi_M=180^\circ-|\phi_C \bmod 360^\circ|$. Linear regulators having small but nonzero phase margins, e.g., <30°, are susceptible to excessive ringing in the output voltage when a load transient occurs. Larger phase margins, e.g., 45°≤ ϕ_M ≤60°, lead to faster settling of the output voltage after a load transient.

Each pole introduces a phase shift of -90°, whereas a zero introduces a phase shift of +90°. A linear regulator typically has at least an internal pole and a pole associated with the output load and output capacitor. Compensation networks, which may introduce zeros or move the frequency of a pole, must often be designed into or added to a linear regulator, to ensure stable operation of the linear regulator, i.e., that adequate phase margin is achieved.

The pole associated with the output capacitor and the output load resistance presents particular difficulties, as the output load resistance effectively varies as the load current

varies. This leads to a pole frequency that varies with current. Compensation networks to address such a varying pole frequency are typically designed to provide adequate phase margin over an expected range of load current. The resultant linear regulator may only be stable (have adequate phase margin) within a fairly limited current range.

Compensation networks are desired that provide stability for linear regulators over a wide range of output current.

10

SUMMARY

According to an embodiment of a compensation network, the compensation network is configured to improve stability of an operational amplifier by providing a variable-frequency zero in a frequency response of the operational amplifier. The compensation network comprises an input, a first resistance branch, a second resistance branch, and a current source. The input is for coupling to an output of the operational amplifier. The first and second resistance branches are coupled to the operational amplifier output. The first resistance branch includes a series resistor, whereas the second resistance branch, which is coupled in parallel to the first resistance branch, includes a parallel resistor. The current source is configured to supply current to the first and/or second resistance branches of the compensation network. The compensation network provides a variable impedance to the input, wherein the variable impedance includes a resistance that varies between a lower resistance that is based upon a resistance of the series resistor, and an upper bound that is based upon a resistance of the parallel resistor. For example, the variable resistance may be bounded between the resistances of the series and parallel resistors. The variable resistance is based upon a resistance control signal.

According to an embodiment of a linear voltage regulator, the regulator comprises an input for coupling to an input power source, an output for coupling to a load and a load capacitor, a pass switch, an error amplifier, and a compensation network. The pass switch is configured to pass current from the input to the output based upon a pass control signal at a pass control terminal of the pass switch. The error amplifier is configured to generate the pass control signal based upon a difference between a reference voltage and a feedback voltage which follows an output voltage of the linear voltage regulator, and is configured to output the pass control signal at an error amplifier output. The compensation network is configured as described above, and has an input that is coupled to the error amplifier output of the linear voltage regulator.

According to an embodiment of a method for frequency compensating a linear voltage regulator which includes an error amplifier and a compensation network coupled to an output of the error amplifier, the method includes sensing an output current of the linear voltage regulator and generating a switch control signal based upon this sensed output current. The generated switch control signal is applied to a resistance control switch of the compensation network, so as to control a level of current flow through a series resistor of the compensation circuit such that a zero frequency of the compensation network varies linearly with the output current. The method results in a zero frequency that varies linearly with the output current of the linear voltage regulator.

Those skilled in the art will recognize additional features and advantages upon reading the following detailed description, and upon viewing the accompanying drawings.

BRIEF DESCRIPTION OF THE FIGURES

The elements of the drawings are not necessarily to scale relative to each other. Like reference numerals designate corresponding similar parts. The features of the various illustrated embodiments may be combined unless they exclude each other. Embodiments are depicted in the drawings and are detailed in the description that follows.

FIG. 1 illustrates a schematic diagram of a low dropout (LDO) linear voltage regulator.

FIGS. 2A and 2B illustrate frequency responses for the gain loops in different voltage regulators.

FIG. 3 illustrates a schematic diagram of a compensation network, as may be used in the voltage regulator of FIG. 1.

FIG. 4A illustrates an idealized mapping of current through a transistor to the drain-source voltage across the transistor for a particular gate-to-source voltage.

FIG. 4B illustrates an output resistance, as a function of input current, for the variable resistor within the compensation network of FIG. 3.

FIG. 5 illustrates a schematic diagram of an LDO linear voltage regulator which includes a compensation network as illustrated in FIG. 3.

FIG. 6 illustrates a frequency response for the voltage regulator of FIG. 5.

FIG. 7 illustrates a method for providing a zero to stabilize a linear voltage regulator.

DETAILED DESCRIPTION

The embodiments described herein provide compensation networks and associated methods for compensating frequency and phase responses of a linear regulator, so as to ensure stable operation of the regulator over a wide range of output current. The embodiments are described primarily in the context of a low dropout (LDO) linear regulator using a p-channel metal-oxide semiconductor field-effect transistor (pMOSFET) as a pass device. However, the invention is not limited to LDO regulators based upon such a pass device. For example, the described compensation networks could be readily used with LDO regulators using PNP bipolar junction transistors (BJTs), which have similar impedance characteristics (and associated poles), as pMOSFET pass devices. Furthermore, linear regulators using other types of pass devices, e.g., NPN BJTs, n-channel MOSFETs, could also advantageously use the compensation networks described below. Yet further, the described compensation network could be used to stabilize operational amplifiers that are not part of a voltage regulator.

The embodiments are described below by way of particular examples of compensation network circuitry, linear regulator circuitry, and methods for stabilizing an amplifier. It should be understood that the below examples are not meant to be limiting. Circuits and techniques that are well-known in the art are not described in detail, so as to avoid obscuring unique aspects of the invention. Features and aspects from the example embodiments may be combined or re-arranged, except where the context does not allow this.

FIG. 1 illustrates an embodiment of an LDO linear voltage regulator 100 comprising an error amplifier 110, a voltage buffer 120, a pass device P1, and a voltage divider including resistors R₁ and R₂. Power is provided to the voltage regulator 100 from an input 102 having voltage V_{IN},

and power is provided to a load at an output 104. The load of the regulator 100 is modelled as a resistor

$$5 \quad R_L = \frac{V_{OUT}}{I_L},$$

where I_L is the load current. Because the current I_L drawn by the load varies over time while the voltage V_{OUT} at the output 104 remains substantially constant, the resistance of the load resistor R_L varies. A load capacitor C_L is also connected to the output 104, and serves to smooth the output voltage V_{OUT} by sourcing current during load transients, thereby improving transient performance of the regulator 100. The load capacitor C_L is modelled as having an equivalent series resistance (ESR), which is shown as R_{ESR}. The output voltage V_{OUT} is set by the resistors R₁ and R₂, and a reference voltage V_{REF}, such that

$$V_{OUT} = \left(1 + \frac{R_2}{R_1}\right) * V_{REF}.$$

The illustrated error amplifier 110 is modelled as an operational transconductance amplifier (OTA) having transconductance g_{ma} and output impedance r_{oa}. The buffer 120 serves to isolate the error amplifier 110 from the pass device P1 and, as illustrated, has unity gain and an output impedance

$$35 \quad \frac{1}{g_{mbuf}}.$$

The input capacitance of the pass device P1 is modelled using a pass capacitance C_P. The input capacitance of the buffer 120 may be modelled using a capacitor C_{BUF}, which is not explicitly shown for ease of illustration, but which may be considered part of compensation network 130. Such a modelled input capacitance C_{BUF} would be connected between the input of the buffer 120 and ground.

The compensation network 130 connects to the output of the error amplifier 110. Further detail regarding circuitry for the compensation network 130 is provided in conjunction with the embodiments of FIGS. 3 and 5. Before considering these embodiments, the open loop gain of an uncompensated voltage regulator similar to that in FIG. 1 is explained. Such an open loop gain may be expressed as:

$$55 \quad G_{LOOP}(s) \cong \frac{1}{g_{mbuf}}. \quad (1)$$

$$\frac{R_2}{R_1 + R_2} g_{ma} r_{oa} g_{mp} R_L \frac{(sR_{ESR} C_L + 1)}{(sR_L C_L + 1)(s r_{oo} C_{BUF} + 1) \left(s \frac{C_P}{g_{mbuf}} + 1 \right)},$$

where g_{mp} is the transconductance of the pass device P1 and C_{BUF} is a parasitic input capacitance of the buffer 120. As shown in equation (1), the uncompensated voltage regulator has three poles and one zero at the following locations:

$$65 \quad p_{CL} = \frac{1}{sR_L C_L} = \frac{I_L}{sV_{OUT} C_L}, \quad (2)$$

-continued

$$p_{CBUF} = \frac{1}{sR_{oa}C_{BUF}}, \quad (3)$$

$$p_{CP} = \frac{g_{mbuf}}{sC_P}, \text{ and} \quad (4)$$

$$z_{CL} = \frac{1}{sR_{ESR}C_L}. \quad (5)$$

As shown in equation (2), the pole p_{CL} associated with the output node 104, i.e., the pole provided by the parallel connection of the load resistor R_L and the load capacitor C_L , has a frequency that is directly proportional to the load current I_L . A load current I_L varying between a minimum current level “low I_L ” and a maximum current level “high I_L ” results in a corresponding frequency shift for the pole p_{CL} , as illustrated in the Bode plot 200 of FIG. 2A. The Bode plot 200 shows a magnitude response 210L and phase response 220L for the case when the load current I_L is at its minimum level “low I_L .” Also shown are a magnitude response 210H and phase response 220H for the case when the load current I_L is at its maximum level “high I_L .” Frequencies corresponding to the output pole p_{CL} for low and high load currents are shown, as are frequencies for pole p_{CBUF} , pole p_{CP} and zero z_{CL} as described by equations (2)-(5). The Bode plot 200 also illustrates the effect of other high-frequency (HF) poles, but these are not particularly relevant as they occur at frequencies higher than the 0 dB gain frequency.

As shown in the Bode plot 200, each pole p_{CL} , p_{CBUF} , p_{CP} introduces a phase shift of -90° , whereas the zero z_{CL} introduces a phase shift of $+90^\circ$. The illustrated phase responses 220L, 220H are relative to a theoretically ideal phase, such that the respective phase differences at the 0 dB (unity gain) frequency between these responses 220L, 220H and the illustrated negative 180° represent the phase margin of the system. In other words, the illustrated negative 180° represents a worst case of no phase margin, whereas 0° represents maximum phase margin. As shown in the phase response 220L, there is no phase margin 222L for the “low I_L ” case, i.e., the phase at the frequency where the gain crosses 0 dB is 180° out of phase, meaning the system is unstable for this condition. The phase response 220H corresponding to the “high I_L ” current shows a phase margin 222H of 45°. For load current levels between these extremes, the phase margin will be between 0° and 45°. Such a system must be compensated to achieve acceptable stability. However, the variation in the frequency of the pole p_{CL} creates difficulties for such compensation and/or limits the range of the output current I_L over which stable operation is achieved.

A common technique for stabilizing a linear regulator is to choose a load capacitor C_L having a high ESR, such that the corresponding zero z_{CL} moves lower in frequency. Another technique, which may be used as an alternative to or in conjunction with choosing a high-ESR capacitor C_L , is to introduce a compensation capacitor C_C and compensation resistor R_C , which are connected to the output of the error amplifier 110. These components provide another zero which may be used to compensate for the phase shift of the load pole p_{CL} . (The compensation capacitor C_C and compensation resistor R_C are connected in series and are internally connected to the regulator in place of the compensation network 130 shown in FIG. 1.) The compensation capacitor

C_C is chosen to be much larger than the input capacitance C_{BUF} of the buffer 120, such that the input capacitance C_{BUF} may be neglected.

By choosing a sufficiently large capacitance for the compensation capacitor C_C and taking advantage of the relatively high output impedance of the error amplifier 110, the compensation pole p_{C_c} , which replaces the p_{CBUF} of the uncompensated system, becomes the dominant pole and has a frequency lower than that of the (moving) output pole p_{CL} . (This is in contrast to the uncompensated system, in which the pole p_{CBUF} has a frequency within the range of frequencies for the output pole p_{CL} .) The compensation zero z_{C_c} created by the compensation capacitor C_C and compensation resistor R_C may be used to nullify, to a large extent, the phase shift of the moving output pole p_{CL} . The resulting loop gain contains three poles and two zeros, as given by:

$$p_{CL} = \frac{1}{sR_L C_L} = \frac{I_L}{sV_{OUT} C_L}, \quad (6)$$

$$p_{C_c} = \frac{1}{sR_{oa} C_C}, \quad (7)$$

$$p_{CP} = \frac{g_{mbuf}}{sC_P}, \quad (8)$$

$$Z_{C_c} = \frac{1}{sR_C C_C}, \text{ and} \quad (9)$$

$$z_{CL} = \frac{1}{sR_{ESR} C_L}. \quad (10)$$

A typical Bode plot 250 for such a system is shown in FIG. 2B. Here it can be seen that the compensation pole p_{C_c} is the dominant pole having a very low frequency, and that the compensation zero z_{C_c} falls within the range of the moving output pole p_{CL} , thereby partially compensating for the phase shifts of the compensation pole p_{C_c} and the output pole p_{CL} . Magnitude responses 260L, 260H corresponding, respectively, to “low I_L ” and “high I_L ” load currents are illustrated, as are phase responses 270L, 270H.

While a system using compensation as described above represents an improvement over an uncompensated system, the Bode plot 250 of FIG. 2B shows that there is still a significant variance in the phase margin caused by the varying load current I_L . In particular, the illustrated phase margins 272L, 272H for the “low I_L ” and “high I_L ” cases are, respectively, 90° and 45°. It is quite difficult to find a single value for the compensation resistor R_C that can ensure good phase margin (PM) for the entire range between the high and low load currents. This problem becomes more challenging when also considering component variations that occur over process and temperature. Notably, the load capacitor C_L may have a high tolerance, e.g., $-20\% / +80\%$, which further widens the potential range of frequencies for the output pole p_{CL} . To ensure a stable system (good phase margin), high-accuracy, temperature-stable components must be used and/or only a narrow range of load current I_L may be supported. Both of these constraints are undesirable.

Another compensation technique replaces the compensation resistor R_C described above with a transistor operating in its triode region, thereby acting as a variable resistor. The transistor's conductance is controlled based on the load current, thereby providing a zero that varies with the load current. Whereas the load pole p_{CL} varies linearly with the output current I_L , such a zero only varies with the square root of the output current I_L . While this provides an improvement

over compensation techniques relying upon a fixed zero, the range of load current I_L over which stability is ensured is still not as wide as desired.

The variable resistor 340 of FIG. 3 may be used to generate a zero that varies linearly with the load current I_L . Such a zero may be used to closely track the load pole p_{CL} , which also varies linearly with the load current I_L . By using such a zero within the voltage regulator 100, the range of load current I_L over which stability is ensured is wider than the stable current range provided by the circuits and techniques previously known. Stated alternatively, use of a zero that linearly tracks the load current I_L provides better phase margin (PM) than other compensation techniques.

FIG. 3 illustrates a compensation network 330 which includes a variable resistor 340 and a control signal generator 350. The variable resistor 340 may be controlled to provide an output resistance r_{out} at a node 344. This resistance r_{out} is inversely proportional to a control current I_{IN} , at least within a selected range of the control current I_{IN} .

The variable resistor 340 includes a series resistor R_S , a parallel resistor R_P , and a biasing current source 342. The biasing current source 342 provides a constant bias current I_B . A transistor N2 controls current conduction through the series resistor R_S , so as to determine how the current I_B is split between the series resistor R_S and the parallel resistor R_P . The transistor N2 is configured to mirror a current I_{N1} flowing through a transistor N1, such that the current I_{N1} ultimately controls the current split between the series resistor R_S and the parallel resistor R_P , and the resultant output resistance r_{out} . The control signal generator 350 includes, in addition to the transistor N1, an input current source which provides a typically variable current I_{IN} , and an input biasing current sink 352 which sinks a current I_{IN_BIAS} . (The input biasing current sink 352 is optional, and may not be included in some implementations. In other implementations, the current I_{IN_BIAS} of the current sink 352 could be negative, in which case the current sink 352 sources current.) For embodiments including the input biasing current sink 352, the current I_{N1} through transistor N1 is given by $I_{N1} = I_{IN} - I_{IN\_BIAS}$.

To further explain the operation of the variable resistor 340, assume that $R_S \ll R_P$ and consider the effect of the input current I_{IN} on the output resistance r_{out} . If the input current I_{IN} is not greater than the input bias current I_{IN_BIAS} , no current flows through N1 and the transistors N1 and N2 will remain off. All of the bias current I_B will flow through the parallel resistor R_P , the circuit branch comprising the series resistance R_S and the transistor N2 is effectively open-circuited. For such an input current, the output resistance $r_{out} \approx R_P$.

Conversely, consider the other extreme, i.e., when the input current I_{IN} is very high. While the transistor N1 may operate in its saturation (fully on) region for this condition, the current I_{N2} through the transistor N2 is limited by the drain-source voltage V_{DS_N2} of the transistor N2. (This is further explained below in the description of FIG. 4A.) This limitation means that the current I_{N2} through transistor N2 is not able to properly mirror the current I_{N1} as is the case when both transistors are operating in their saturation regions. For this condition, the transistor N2 operates in its triode region, wherein it may be modelled as having a small resistance R_{DSON_N2} . Assuming this resistance $R_{DSON\_N2} \ll R_S$, the output resistance r_{out} may be approximated as the resistance of the series resistor R_S , i.e., $r_{out} \approx R_S$.

FIG. 4A illustrates an idealized mapping 400 of the drain-source current I_{N2} as a function of the drain-source voltage V_{DS_N2} of transistor N2, for a given gate voltage

V_{GS_N2} of the transistor N2. In the triode region, the voltage-current mapping is modelled (approximated) as being linear. For voltages higher than $V_{DS\_N2\_SAT}$, the transistor N2 operates in its saturated mode, wherein it is approximated that a saturation current I_{N2_SAT} flows through transistor N2 regardless of the drain-source voltage V_{DS_N2} . A corresponding current level, denoted

$$I_{N1} |_{V_{DS\_N2} \geq V_{DS\_N2\_SAT}},$$

flows through the transistor N1 when the drain-source voltage V_{DS_N2} of transistor N2 is at or above its saturation voltage $V_{DS\_N2\_SAT}$, and an associated input current level, denoted

$$I_{IN} |_{V_{DS\_N2} \geq V_{DS\_N2\_SAT}},$$

is related to the current level

$$I_{N1} |_{V_{DS\_N2} \geq V_{DS\_N2\_SAT}},$$

30 by the input bias current level I_{IN_BIAS} .

For an input current I_{IN} within the nominal range

$$I_{IN\_BIAS} < I_{IN} < I_{IN} |_{V_{DS\_N2} \geq V_{DS\_N2\_SAT}},$$

the output resistance r_{out} is a function of R_S , R_P , and the output resistance r_{o_N2} of transistor N2. In contrast to the case described above, the output resistance r_{o_N2} of transistor N2 is not negligible for this scenario. The output resistance r_{out} for this case may be expressed as:

$$r_{out} = R_P \parallel (R_S + r_{o\_N2}) = \frac{R_P(R_S + r_{o\_N2})}{R_P + R_S + r_{o\_N2}}. \quad (11)$$

For input current within the range

$$I_{IN\_BIAS} < I_{IN} < I_{IN} |_{V_{DS\_N2} \geq V_{DS\_N2\_SAT}},$$

55 or, equivalently,

$$I_{IN\_BIAS} < I_{IN} < I_{N1} |_{V_{DS\_N2} \geq V_{DS\_N2\_SAT}} + I_{IN\_BIAS},$$

60 the transistor N2 will operate in its saturation region and mirror the current I_{N1} . Because the transistor N2 is operating in its saturation mode, its output resistance r_{o_N2} will be quite high. More particularly, $R_S \ll r_{o\_N2}$ for this range of input current, so that the series resistance R_S may be neglected. Equation (11) may thus be simplified to:

$$r_{out} \cong R_P \frac{r_{o\_N2}}{R_P + r_{o\_N2}} = R_P \frac{1}{\frac{R_P}{r_{o\_N2}} + 1}. \quad (12)$$

The resistance r_{o_N2} may be approximated by the ratio of the Early voltage V_E of the transistor N2 to the current flowing through this transistor, i.e.,

$$r_{o\_N2} \cong \frac{V_E}{I_{N2}} = \frac{V_E}{I_{IN} - I_{IN\_BIAS}}$$

for $I_{N1} = I_{N2}$. (For the 1:1 current mirror illustrated in FIG. 3, the currents through the transistors N1 and N2 should mirror each other when both transistors are operating in the same mode, e.g., saturated.) Substituting this approximation into equation (12) yields:

$$r_{out} \cong R_P \frac{1}{\frac{R_P}{V_E} (I_{IN} - I_{IN\_BIAS}) + 1}. \quad (13)$$

The transistors N1, N2 shown in FIG. 3 are n-channel MOSFETs. It should be understood that the circuit topology of the compensation network 330 could be modified to use other types of transistors, e.g., pMOSFETs, NPN BJTs, PNP BJTs, to create a current mirror or similar, and that other types of transistors may be preferred in some applications.

FIG. 4B illustrates a plot 410 of the output resistance r_{out} as a function of the input current I_{IN} . As explained above and shown in FIG. 4, the output resistance r_{out} may be approximated as R_P for small values of the input current I_{IN} , and may be approximated as R_S for large values of

$$I_{IN}, \text{ i.e., } I_{IN} > I_{IN} |_{V_{DS\_N2} \geq V_{DS\_N2\_SAT}}.$$

For input current I_{IN} within the nominal range described above, the output resistance r_{out} is inversely proportional to the input current I_{IN} , as indicated in equation (13) and as shown in the “saturation region” of the plot 410. This property of the variable resistor 340 may be used to construct a zero that is able to efficiently track and compensate for the output pole p_{CL} , whose frequency moves linearly with the load current I_L .

FIG. 5 illustrates an LDO voltage regulator 500 that makes use of a variable resistor, such as the variable resistor 340 described above, to introduce a zero to the gain loop for the regulator 500. A compensation network 530 includes the variable resistor 340, a control signal generator 550, and a compensation capacitor C_{COMP} , which couples the output of the error amplifier 110 to the variable resistor 340. The capacitance of the compensation capacitor C_{COMP} is much larger than the parasitic input capacitance of the buffer 120, such that this parasitic capacitance may be neglected. The control signal generator 550 uses current mirrors M1, M2 to provide a resistance control signal to the transistor N2 of the variable resistor 340. The first current mirror M1 includes a pMOSFET P2 configured to mirror the current through the pass device P1, which is also a pMOSFET. For values of R_1 and R_2 much greater than the load resistance R_L , as is typical, the current through the pass device P1 may be

approximated as the load current I_L . The MOSFETs P2 and P1 are sized 1:K, such that the current flowing through MOSFET P2 is approximately I_L/K . The second current mirror M2 includes MOSFETs N2 and N1, which are sized 1:H. Other transistor types could be used in the first current mirror M1, but the second transistor P2 is typically the same transistor type as the pass device P1. Other transistor types may also be used in the second current mirror M2.

The series connection of the compensation capacitor C_{COMP} with the variable resistor 340, which has a resistance r_{out} , provides a compensation zero given by:

$$z_{COMP} = \frac{1}{s r_{out} C_{COMP}}. \quad (14)$$

As explained previously and shown in FIG. 4B, the resistance r_{out} varies between a high value of the parallel resistance R_P and a low value of the series resistance R_S . Minimum and maximum frequencies for the compensation zero are thus given by:

$$z_{COMP}^{MIN} = \frac{1}{s R_P C_{COMP}}, \text{ for } I_L < K \cdot I_{IN\_BIAS}, \text{ and} \quad (15)$$

$$z_{COMP}^{MAX} = \frac{1}{s R_S C_{COMP}}, \text{ for } I_L > I_{IN} |_{V_{DS\_N2} \geq V_{DS\_N2\_SAT}} \cdot H \cdot K + I_{IN\_BIAS} \cdot K. \quad (16)$$

Note that the input current I_{IN} shown in FIG. 3 is related to the load current I_L of FIG. 5 according to

$$I_{IN} \cong \frac{I_L}{K},$$

and that the current

$$I_{N2} = \frac{I_{N1}}{H}$$

for transistors N1, N2 operating in the same region, where H and K are current ratios for the current mirrors M1, M2. Within the range

$$K \cdot I_{IN\_BIAS} < I_L < H \cdot K \cdot (I_{IN} |_{V_{DS\_N2} \geq V_{DS\_N2\_SAT}}) + K \cdot I_{IN\_BIAS},$$

the frequency of the compensation zero may be found by combining equations (13) and (14) and taking the current mirror ratios into account to yield:

$$z_{COMP} \cong \frac{\left(\frac{R_P}{HV_E} \left(\frac{I_L}{K} - I_{IN\_BIAS} \right) + 1 \right)}{s R_P C_{COMP}}. \quad (17)$$

Equation (17) shows that the frequency of the compensation zero is linearly proportional to the load current I_L . Given that the output pole p_{CL} is also linearly proportional to the load current I_L , the compensating zero provided by the compensation network 530 can track the output pole p_{CL} quite accurately.

FIG. 6 illustrates a Bode plot 600 of the gain loop for the LDO voltage regulator 500, which makes use of the compensation network 530. Note that both the output pole p_{CL} and the compensation zero z_{COMP} vary similarly over frequency as the load current I_L varies from “low I_L ” to “high I_L .” The phase margin (PM) remains within a good range and has limited dependency on the load current I_L . For the illustrated example, the phase margin 622L for the “low I_L ” case and the phase margin 622H for the “high I_L ” case are the same, i.e., 90°, but the phase margin increases to 135° at the zero z_{CL} corresponding to the output capacitor C_L and its resistance R_{ESR} . Note that this is a significant improvement over the phase margins illustrated in FIG. 2A, which vary from 0° to 45°, and FIG. 2B, where the phase margin varies from 45° to 135°. The phase margin for the voltage regulator 500 may even be kept constant and independent of load current I_L , via appropriate choice of component values.

The LDO voltage regulator 500 is very flexible and the compensation network 530 offers any degrees of freedom that are not available with prior compensation techniques. In particular, the gain loop and associated phase margins may be modified as needed using the series resistance R_S , the parallel resistance R_P , the input bias current I_{IN_BIAS} , and the transistor size ratios H and K. Via appropriate configuration of these circuit parameters, the frequency response of an LDO voltage regulator may be configured to meet phase margin or similar requirements over a desired range of load current I_L . The range of load current I_L over which good phase margin may be achieved is wider than is available with other compensation methods.

Referring to FIG. 4B, the current I_{IN_BIAS} , which is provided by the current sink 352, may be modified to adjust the transition point 412 between the “off region” and the “saturation region” in the r_{out} vs I_{IN} curve. Adjustments to the transistor size ratios H and K change the slope of the r_{out} vs I_{IN} curve in the saturation region, as illustrated by the arrows 414a. These adjustments similarly alter the transition point 414b between the saturation and triode regions.

Referring to FIG. 6, frequencies for the output pole p_{CL} and the compensation zero z_{COMP} are aligned for the “high I_L ” load current. However, frequencies for the output pole p_{CL} and the compensation zero z_{COMP} are not aligned for the “low I_L ” load current. The bias current I_{IN_BIAS} of the current sink 352, the transistor size ratios H and K, and/or the resistance of the series and parallel resistors R_S , R_P may be configured to align the frequencies of the output pole p_{CL} and the compensation zero z_{COMP} across the range of load current, i.e., from “low I_L ” to “high I_L .”

FIG. 7 illustrates a method for frequency compensating a linear voltage regulator. Such a method may be implemented within a linear voltage regulator, including an error amplifier, such as that illustrated in FIG. 5. The linear voltage regulator further includes a compensation network coupled to an output of the error amplifier.

The method 700 begins by sensing 710 an output current of the linear voltage regulator. For example, a current mirror may be used to mirror a current provided to the load of the voltage regulator. Next, a switch control signal is generated 720 based upon the sensed output current. The generated switch control signal is applied 730 to a resistance control switch of the compensation network. This controls a level of current flowing through a series resistor of the compensation network which, in turn, varies an impedance of the compensation circuit such that a zero frequency of the compensation network varies linearly with the output current.

An embodiment of a compensation network comprises an input, a first resistance branch, a second resistance branch,

and a current source. The input is for coupling to an output of an operational amplifier. The first and second resistance branches are coupled to the operational amplifier output. The first resistance branch includes a series resistor, whereas the second resistance branch, which is coupled in parallel to the first resistance branch, includes a parallel resistor. The current source is configured to supply current to the first and/or second resistance branches of the compensation network. The compensation network provides a variable impedance to the input, wherein the variable impedance includes a resistance that varies between a lower resistance based upon a resistance of the series resistor and an upper resistance based upon a resistance of the parallel resistor, the variable impedance being based upon a resistance control signal. This resistance is based upon a resistance control signal.

According to any embodiment of the compensation network, the first resistance branch comprises a resistance control switch serially connected to the series resistor, and the resistance control switch is configured to control, based upon the resistance control signal, a level of current flowing through the first resistance branch.

According to any embodiment of the compensation network, the operational amplifier is an error amplifier within a linear voltage regulator which supplies a load current to a load, the compensation network further comprising a control signal generation circuit configured to generate the resistance control signal based upon the load current. According to a first sub-embodiment, the first resistance branch comprises a resistance control switch serially connected to the series resistor, and the resistance control switch is configured to control a level of current flowing through the first resistance branch based upon the resistance control signal. The control signal generation circuit comprises a sense switch configured to mirror a pass switch of the linear voltage regulator, the load current flowing through the pass switch and a sense current flowing through the sense switch, and a control signal generator switch coupled to the sense switch such that the sense current flows through the control signal generator switch, the control signal generator switch providing the resistance control signal such that the level of current flowing through the resistance control switch mirrors the sense current. According to a second sub-embodiment, which may or may not be combined with the first sub-embodiment, the variable-frequency zero is selected to track a frequency of a pole associated with an output of the linear voltage regulator, wherein the pole frequency is proportional to the load current.

An embodiment of a linear voltage regulator comprises an input for coupling to an input power source, an output for coupling to a load and a load capacitor, a pass switch, an error amplifier, and a compensation network. The pass switch is configured to pass current from the input to the output based upon a pass control signal at a pass control terminal of the pass switch. The error amplifier is configured to generate the pass control signal based upon a difference between a reference voltage and a feedback voltage which follows an output voltage of the linear voltage regulator, and is configured to output the pass control signal at an error amplifier output. The compensation network is configured as described above, and has an input that is coupled to the error amplifier output of the linear voltage regulator.

According to any embodiment of the linear voltage regulator, the first resistance branch comprises a resistance control switch serially connected to the series resistor, and the resistance control switch is configured to control a level of current flowing through the first resistance branch based

13

upon the resistance control signal. According to any sub-embodiment, the pass control signal may be a voltage and the pass control terminal may be a gate.

According to any embodiment of the linear voltage regulator, the current source supplies a constant current and is coupled to the first resistance branch and the second resistance branch such that the constant current is split between a current flowing through the first resistance branch and a current flowing through the second resistance branch, wherein a ratio of these currents is determined by the resistance control signal.

According to any embodiment of the linear voltage regulator, the linear voltage regulator further includes a compensation capacitor which couples the error amplifier output to the first resistance branch and the second resistance branch.

According to any embodiment of the linear voltage regulator, the linear voltage regulator further includes a control signal generation circuit configured to generate the resistance control signal based upon a load current supplied at the output. According to any sub-embodiment of the linear voltage regulator that includes the control signal generation circuit, the control signal generation circuit includes a current source. According to any sub-embodiment of the linear voltage regulator that includes the control signal generation circuit, the first resistance branch comprises a resistance control switch serially connected to the series resistor, and the resistance control switch is configured to control a level of current flowing through the first resistance branch based upon the resistance control signal, and the control signal generation circuit comprises a sense switch configured to mirror the pass switch, a pass current flowing through the pass switch and a sense current flowing through the sense switch; and a control signal generator switch coupled to the sense switch such that the sense current flows through the control signal generator switch, the control signal generator switch providing the resistance control signal such that the level of current flowing through the resistance control switch mirrors the sense current. According to any sub-embodiment of the linear voltage regulator that includes the control signal generation circuit, the sense switch and the pass switch are configured such that the sense current is K times less than the pass current and K is greater than one, and the control signal generator switch and the resistance control switch are configured such that the level of current flowing through the resistance control switch is H times less than the sense current and H is greater than one, when the control signal generator switch and the resistance control switch are operating in a same mode. According to any sub-embodiment of the linear voltage regulator that includes the control signal generation circuit, the pass switch and the sense switch are p-channel metal-oxide semiconductor field-effect transistors (pMOSFETs) or the pass switch and the sense switch are bipolar junction transistors (BJTs).

An embodiment of a method for frequency compensating a linear voltage regulator which includes an error amplifier and a compensation network coupled to an output of the error amplifier includes sensing an output current of the linear voltage regulator and generating a switch control signal based upon this sensed output current. The generated switch control signal is applied to a resistance control switch of the compensation network, so as to control a level of current flow through a series resistor of the compensation network. This, in turn, varies an impedance of the compensation circuit such that a zero frequency of the compensation network varies linearly with the output current. The method

14

results in a zero frequency that varies linearly with the output current of the linear voltage regulator.

According to any embodiment of the method, the method further comprises supplying a constant current to the compensation network and splitting the supplied constant current between the series resistor and a parallel resistor of the compensation network, such that the ratio of these currents is determined by the switch control signal.

According to any embodiment of the method, the impedance of the compensation circuit varies such that the zero frequency of the compensation network tracks a pole frequency of the linear voltage regulator.

As used herein, the terms "having," "containing," "including," "comprising," and the like are open-ended terms that indicate the presence of stated elements or features, but do not preclude additional elements or features. The articles "a," "an" and "the" are intended to include the plural as well as the singular, unless the context clearly indicates otherwise.

It is to be understood that the features of the various embodiments described herein may be combined with each other, unless specifically noted otherwise.

Although specific embodiments have been illustrated and described herein, it will be appreciated by those of ordinary skill in the art that a variety of alternate and/or equivalent implementations may be substituted for the specific embodiments shown and described without departing from the scope of the present invention. This application is intended to cover any adaptations or variations of the specific embodiments discussed herein. Therefore, it is intended that this invention be limited only by the claims and the equivalents thereof.

What is claimed is:

1. A compensation network configured to improve stability of an operational amplifier by providing a variable-frequency zero in a frequency response of the operational amplifier, the compensation network comprising:

an input for coupling to an output of the operational amplifier;

a first resistance branch coupled to the operational amplifier output and comprising a series resistor;

a second resistance branch coupled in parallel to the first resistance branch and comprising a parallel resistor; and

a current source configured to supply current to the compensation network,

wherein the compensation network provides a variable impedance to the input, the variable impedance having a resistance that varies between a lower resistance based upon a resistance of the series resistor and an upper resistance based upon a resistance of the parallel resistor, the variable impedance being based upon a resistance control signal.

2. The compensation network of claim 1, wherein the first

resistance branch comprises a resistance control switch serially connected to the series resistor, and the resistance control switch is configured to control, based upon the resistance control signal, a level of current flowing through the first resistance branch.

3. The compensation network of claim 1, wherein the current source supplies a constant current and is coupled to the first resistance branch and the second resistance branch such that the constant current is split between a current flowing through the first resistance branch and a current flowing through the second resistance branch, wherein a ratio of these currents is determined by the resistance control signal.

15

4. The compensation network of claim 1, wherein the operational amplifier is within a voltage regulator which supplies a load current to a load, the compensation network further comprising:

a control signal generation circuit configured to generate the resistance control signal based upon the load current.

5. The compensation network of claim 4, wherein the first resistance branch comprises a resistance control switch serially connected to the series resistor, and the resistance control switch is configured to control a level of current flowing through the first resistance branch based upon the resistance control signal, and

wherein the control signal generation circuit comprises: a sense switch configured to mirror a pass switch of the voltage regulator, the load current flowing through the pass switch and a sense current flowing through the sense switch; and

a control signal generator switch coupled to the sense switch such that the sense current flows through the control signal generator switch, the control signal generator switch providing the resistance control signal such that the level of current flowing through the resistance control switch mirrors the sense current.

6. The compensation network of claim 4, wherein the variable-frequency zero is selected to track a frequency of a pole associated with an output of the voltage regulator; wherein the pole frequency is proportional to the load current.

7. A linear voltage regulator; comprising:

an input for coupling to an input power source; an output for coupling to a load and a load capacitor; a pass switch configured to pass current from the input to the output based upon a pass control signal at a pass control terminal of the pass switch;

an error amplifier configured to generate the pass control signal based upon a difference between a reference voltage and a feedback voltage which follows an output voltage of the linear voltage regulator, and configured to output the pass control signal at an error amplifier output; and

a compensation network comprising:

a compensation network input for coupling to the error amplifier output;

a first resistance branch coupled to the error amplifier output and comprising a series resistor;

a second resistance branch coupled in parallel to the first resistance branch and comprising a parallel resistor; and

a current source configured to supply current to the compensation network,

wherein the compensation network provides a variable impedance to the compensation network input, the variable impedance having a resistance that varies between a lower resistance based upon a resistance of the series resistor and an upper resistance based upon a resistance of the parallel resistor, the variable impedance being based upon a resistance control signal.

8. The linear voltage regulator of claim 7, wherein the first resistance branch comprises a resistance control switch serially connected to the series resistor, and the resistance control switch is configured to control a level of current flowing through the first resistance branch based upon the resistance control signal.

16

9. The linear voltage regulator of claim 8, wherein the pass control signal is a voltage and the pass control terminal is a gate.

10. The linear voltage regulator of claim 7, wherein the current source supplies a constant current and is coupled to the first resistance branch and the second resistance branch such that the constant current is split between a current flowing through the first resistance branch and a current flowing through the second resistance branch, wherein a ratio of these currents is determined by the resistance control signal.

11. The linear voltage regulator of claim 7, further comprising:

15 a compensation capacitor which couples the error amplifier output to the first resistance branch and the second resistance branch.

12. The linear voltage regulator of claim 7, further comprising:

20 a control signal generation circuit configured to generate the resistance control signal based upon a load current supplied at the output.

13. The linear voltage regulator of claim 12, wherein the control signal generation circuit comprises a current source.

14. The linear voltage regulator of claim 12, wherein the first resistance branch comprises a resistance control switch serially connected to the series resistor, and the resistance control switch is configured to control a level of current flowing through the first resistance branch based upon the resistance control signal, and

wherein the control signal generation circuit comprises: a sense switch configured to mirror the pass switch, a pass current flowing through the pass switch and a sense current flowing through the sense switch; and a control signal generator switch coupled to the sense switch such that the sense current flows through the control signal generator switch, the control signal generator switch providing the resistance control signal such that the level of current flowing through the resistance control switch mirrors the sense current.

15. The linear voltage regulator of claim 14, wherein the sense switch and the pass switch are configured such that the sense current is K times less than the pass current and K is greater than one, and

wherein the control signal generator switch and the resistance control switch are configured such that the level of current flowing through the resistance control switch is H times less than the sense current and H is greater than one, when the control signal generator switch and the resistance control switch are operating in a same mode.

16. The linear voltage regulator of claim 14, wherein the pass switch and the sense switch are p-channel metal-oxide semiconductor field-effect transistors (pMOSFETs).

17. The linear voltage regulator of claim 14, wherein the pass switch and the sense switch are bipolar junction transistors (BJTs).

18. A method for frequency compensating a linear voltage regulator which includes an error amplifier and a compensation network coupled to an output of the error amplifier, the method comprising:

sensing an output current of the linear voltage regulator; generating a switch control signal based upon the sensed output current; and

applying the generated switch control signal to a resistance control switch of the compensation network,

thereby controlling a level of current flow through a series resistor of the compensation network based upon the generated switch control signal, so as to vary an impedance of the compensation circuit such that a zero frequency of the compensation network varies linearly 5 with the output current.

19. The method of claim 18, further comprising: supplying a constant current to the compensation network; and splitting the supplied constant current between the series 10 resistor and a parallel resistor of the compensation network, such that the ratio of these currents is determined by the switch control signal.

20. The method of claim 18, wherein the impedance of the compensation circuit varies such that the zero frequency of 15 the compensation network tracks a pole frequency of the linear voltage regulator.
